REFORMING GASOLINE

Weldon Grant Annable, Mundelein, Ill., assignor
to The Pure Oil Company, Chicago, Ill., a cor-
poration of Ohio

Application December 4, 1947, Serial No. 789,598

4 Claims. (Cl. 196—50)

1

This invention relates to a method for converting gasoline fractions of low octane rating to gasoline of higher octane rating.

At the present time it is not economically feasible to produce gasoline by thermal cracking or reforming operations having an octane number appreciably above 70 motor method because of the excessive losses resulting when an attempt is

5

tion contains a large portion of low octane number paraffin and naphthalene hydrocarbons. The following table shows the analysis on eight different gasoline samples. The first five samples are thermally cracked gasolines; sample six is a reformate from a thermal reforming operation; and samples seven and eight are straight run gasolines.

Table

Material:	1	2	3	4	5	6	7	8
Light Fraction:								
Per Cent of Total Gasoline	46.4	44.5	64.1	52.5	41.8	46.1	47.7	50.4
Motor Octane No.	72.4	72.8	73.4	75.7	72.6	75.0	66.7	64.6
Heavy Fraction:								
Per Cent of Total Gasoline	53.6	55.3	35.9	47.5	58.2	53.9	52.3	49.6
Motor Octane No.	57.9	58.4	58.9	59.3	56.4	59.7	56.7	56.7
Paraffins and Naphthalenes in Heavy Fractions:								
Volume, Per Cent	58	51	53	38	55	65	93	91
Motor Octane No.	23.0	15.8	17.4	3.0	15.9	32.7	31.9	30.4
Aromatics and Olefins in Heavy Fraction:								
Volume, Per Cent	42	49	47	62	45	35	7	9
Motor Octane No. (Blending Value)	104	103	129	94	100	110	100	100
Actual Motor Octane No.	270.5	79.1		76.2				

¹Blending value in paraffins and naphthalenes of heavy fraction.

²Determined motor octane numbers of aromatics and olefins extracted from heavy fraction.

made to obtain higher octane number material.

I have discovered that if gasoline of low octane number is properly fractionated to separate the portion which contains the hydrocarbons of low octane number, and these hydrocarbons are separately reformed, gasoline of high octane number approaching that of catalytically cracked or reformed gasoline can be prepared with comparatively small loss of gasoline fraction.

An object of the invention is to provide a method for converting low octane gasoline into gasoline of higher octane number.

Another object of this invention is to provide a method for increasing the octane number of low boiling hydrocarbons without excessive loss of gasoline constituents.

Still other objects of the invention will become apparent from the following description and the accompanying drawing of which the single figure is a diagrammatic showing of apparatus useful for carrying out the invention.

It has been discovered that the low octane number of ordinary straight run and thermally cracked gasolines is caused by concentration of certain paraffins and naphthalenes of low octane number in the high-boiling fraction of the gasoline. The heavy fraction of gasoline, namely, that fraction boiling between approximately 250° and 400° F., may comprise anywhere from 30% to 60% of the total gasoline, and this heavy frac-

25

It is apparent from the table that in every instance the gasoline contained a large portion of heavy paraffins and naphthalenes of low octane number.

30

In accordance with my invention gasoline is separated into a light and heavy fraction and the heavy fraction, if it contains a substantial amount of aromatics, is separated into an aromatic-rich fraction and a fraction rich in paraffins and naphthalenes by means of solvent extraction, extractive distillation, or any other suitable means. The raffinate from the extraction of the heavy fraction is subjected to thermal reforming and the reformate is separated into a heavy and light fraction. Heavy reformate is separated into an aromatic-rich fraction and a fraction rich in paraffins and naphthalenes, and the paraffin and naphthalene-rich fraction is recycled to the reforming operation.

Thus, in accordance with my process only the high boiling, low octane number paraffins and naphthalenes are subjected to reforming, whereas the major portion of the gasoline is blended into the final gasoline without being subjected to reforming treatment. As a result, the loss in gas and tar formation are kept to a relatively small value.

In order to better understand the invention, reference is made to the drawing in which the numeral 1 indicates a line through which naphtha or other oil-containing gasoline is charged

to a fractionating tower 3, after having been heated to a temperature sufficiently high to vaporize the gasoline fractions. The oil charged through line 1 may be straight run naphtha, cracked naphtha, or it may be crude oil containing naphtha fractions. The naphtha or other charging stock enters the fractionator 3 at a temperature of approximately 450°-500° F., and is separated into a vapor overhead fraction boiling up to approximately 250°-300° F. and a condensate having a boiling range of approximately 250°-400° F. The vapor fraction is taken overhead through line 5 and condensed in condenser coil 1, and charged to gasoline storage tank 9. The heavy naphtha fraction boiling between approximately 250°-400° F. is taken from the tower 3 as a side-stream through line 11 controlled by valve 13, and either charged by pump 15 to solvent extractor 17 or charged through line 19 controlled by valve 21 to a reformer charge tank 23. Residue may be withdrawn from tower 3 through line 25 controlled by valve 27.

Whether the heavy condensate from tower 3 will be charged to the solvent extractor or to the reformer charge tank will depend on its content of aromatic hydrocarbons. Where the content of aromatics is low, as in the case of some straight run naphthas such as samples 7 and 8 of the previous table, the entire heavy naphtha fraction will be charged directly to the heavy naphtha charge tank. But where the aromatic content is relatively high, as in the case of cracked gasoline samples and the reformate shown in the foregoing table, the heavy fraction is charged to the solvent extractor where it is subjected to a conventional extraction with liquid sulfur dioxide, furfural, phenol or other known solvent for separating aromatics from paraffin and naphthene hydrocarbons in order to separate the naphtha into two fractions, one of which is predominantly aromatic in nature, and the other of which consists chiefly of saturated hydrocarbons. The raffinate, composed chiefly of saturated hydrocarbons, is withdrawn through line 29 and charged to the reformer charge tank 23. The extract passes to stripper 31 through line 33 wherein the solvent is separated from the extract composed chiefly of aromatic and olefinic hydrocarbons. The solvent is recycled through line 35 to the extractor 17. Fresh solvent may be fed into the extractor 17 through line 37 controlled by valve 39. The extract after separation of solvent therefrom is charged from the stripper 31 through line 41 to gasoline storage tank 9.

Material from reformer charge tank is charged by pump 43 to reforming coil 45 where the material may be subjected to temperatures of approximately 950°-1100° F. under super-atmospheric pressure ranging from approximately 200-2,000 pounds per square inch. In the reforming coil the saturated hydrocarbons undergo conversion to a high percentage of olefinic and aromatic hydrocarbons. From the reforming coil the conversion products pass through valve 47 where pressure is partially reduced to fractionator 49. In the fractionator 49 the reformed products are fractionated into a low-boiling fraction having a boiling range up to approximately 250°-300° F., which is taken from the tower as a condensate through line 51, and sent through valve 53 to gasoline storage tank 9. A heavy condensate boiling between approximately 250° to 400° F. is taken from the tower as a side-stream through line 55 controlled by valve 57 and re-

cycled to solvent extractor 17. Any heavy material formed in the reforming operation may be withdrawn from fractionator 49 through line 59 controlled by valve 61. Gas formed in the reforming operation is withdrawn from fractionator 49 through line 63 controlled by valve 65.

Instead of using solvent extraction to separate aromatics from the saturated hydrocarbons in the heavy fraction, extractive distillation or azeotropic distillation may be used, as, for example, distillation with phenol or methyl alcohol.

As a specific example of the invention, gasoline from a high pressure thermal cracking operation have a motor octane number of 65.0, an initial boiling point of 100° F., and an end point of 400° F., is separated into a light fraction boiling up to 250° F. and comprising 46.4% of the gasoline, and a heavy fraction boiling from 250°-400° F. comprising 53.6% of the total gasoline. The octane number of the low-boiling fraction is 72.4 and of the heavy fraction 52.9 motor method. The heavy fraction is solvent extracted with sulfur dioxide, producing a fraction rich in aromatics and olefins comprising 42% of the total, and having a motor octane blending number of approximately 76. The raffinate, comprising 58% of the heavy fraction, has an octane number of 23.0. Only the raffinate portion of the gasoline is subjected to thermal reforming in a coil operated at a temperature of 1025° F. and a pressure of 700 pounds per square inch for a period of approximately 100 seconds. The product from the reforming operation is separated into a fraction boiling up to approximately 250° F., which is blended with the remaining fractions of the gasoline, and a fraction boiling between approximately 250°-400° F., which is recycled to the sulfur dioxide extraction step. In this operation 92% of the initial gasoline is recovered as gasoline having a motor octane number of 75.0. The loss in gas and heavy products is approximately 8%.

It will be seen, therefore, that by separating from the reformer charging stock only those components which have low octane numbers and subjecting only these components to reforming, an over-all yield of approximately 92% of high octane gasoline with a suitable boiling range is obtained as against a yield of approximately 74% of low end point gasoline if the entire heavy fraction were reformed to obtain a final product of slightly lower octane number.

What is claimed is:

1. The method of preparing gasoline of high octane value consisting of the steps: (1) separating a naphtha fraction having a boiling range corresponding approximately to a gasoline into two fractions, one having a boiling range up to about 300° F. and a second naphtha fraction boiling between about 300° and 400° F., (2) subjecting the said second fraction to a thermal reforming operation, (3) separating the reformed products into a first fraction boiling up to about 300° F., and a second fraction boiling between about 300° and 400° F., (4) separating the last-mentioned fraction into a fraction rich in aromatics and olefins and another fraction rich in paraffinic and naphthenic hydrocarbons, (5) subjecting the said paraffinic and naphthenic fraction to thermal reforming, (6) recovering therefrom a fraction boiling up to approximately 300° F. and a fraction boiling between about 300° and 400° F. rich in aromatics and olefins, and (7) blending together as gasoline the fractions boiling up to about 300° F. and the fractions rich in

aromatics and olefins boiling between about 300° and 400° F.

2. Method in accordance with claim 1 in which the 300° to 400° F. fraction rich in paraffinic and naphthenic hydrocarbons obtained in step (6) is recycled to the first mentioned thermal reforming operation identified as step (2).

3. Method in accordance with claim 1 in which the naphtha fraction boiling between about 300° and 400° F. obtained in step (1) is first separated into a fraction rich in aromatics and olefins and another fraction rich in paraffins and naphthenes, and only the fraction of the naphtha rich in paraffins and naphthenes is subjected to the thermal reforming of step (2).

4. Method in accordance with claim 3 in which the 300° to 400° F. fraction rich in paraffinic and

naphthenic hydrocarbons obtained in step (6) separated from the reformed products obtained in step (5) is recycled to the first mentioned thermal reforming operation identified as step (2).
